LOUIS D. GREGG, OF HACKENSACK, NEW JERSEY, ASSIGNEE TO THE GREGG COMPANY, LIMITED, OF NEW YORK, N. Y., A CORPORATION OF NEW YORK.

CANE CAR AND THE LIKE.

Application filed January 10, 1925. Serial No. 1,648.

This invention relates primarily to rail-way or other cars of the type employed for the transportation of sugar cane, although not necessarily limited to this specific use, and, more particularly, to the closure on the discharge side or end of such cars.

These cars, now more or less standardized both in wood and in steel, comprise an under-frame which is covered with a solid or slat flooring and commonly carries, the cane being usually loaded lengthwise of the car, rigidly mounted thereon solid or open-frame end walls and, in the case of the longer cars, intermediate thereof one or more similar transverse walls dividing the car into a plurality of compartments; and, for the side closure, equipped with stakes removably set into stake-pockets attached usually to both sides of the underframe or, on one or both sides, with some form of side-discharge door pivotally mounted at the top or bottom to swing outwardly about a horizontal longitudinal axis.

As heretofore constructed, however, the cars have all proven unsatisfactory in some respect at least. In order to carry the amount of cane required for their economical use, the older cars, with the three-foot (more or less) ends and sides ordinarily provided have been loaded high above the top of the superstructure, which could only be done by expensive hand labor. When the loading is done by mechanical derricks or other labor-saving devices, the ends and sides of the cars must be made about twice the usual height, or say six feet. This in itself renders unavailable the discharge door hinged on its lower side, since the height (or width) of the door does not permit it to swing down perpendicularly or far enough to be out of the way of the falling cane. Moreover, the increased pressure of the load, the cane instead of being hand-laid being in a more or less jumbled condition when dropped into the cars by the mechanical loaders, is too great for the side stakes supported only at their lower ends in stake-pockets, and hence it has been the practice to further support these taller stakes, at or near their upper ends, by a rigidly mounted horizontal rail. But, while cars equipped with stakes thus supported and cars equipped with discharge doors pivoted at the top can be unloaded by lifting the cane out from the top or by tipping the cars about thirty de-

grees to the side, the fixed rail for bracing the stakes or to which the swinging door is hinged renders impossible the use of either of the two forms of convenient mechanical rakes which have been developed for the purpose of raking the cane from the cars.

With a view to remedying this defect, I have here provided a discharge side—or end—closure having as its essential feature a separable or two-piece horizontal rail, the two sections of which are respectively hinged at their outer ends to the two walls of the car, to swing outwardly thereon, and when moved to closed position are releasably joined at their inner ends to form a rail capable of sustaining the outward thrust of the load. A single rail mounted near the top of the walls is ordinarily used to brace the upper ends of the usual stakes or frames, or of stiff steel plates, which, if desired, may be attached to its sections and which at their lower ends are secured to the side of the underframe in releasing stake-pockets or by a locking bar or other equivalent means. In some cases, however, the vertical members of the closure may be omitted and, in place thereof, an additional rail or rails may be mounted on the walls intermediate the top rail and the underframe. In either case, the closure when released and opened up leaves the entire side of the car clear above the underframe.

The invention will be understood by reference to the accompanying drawings, in which—

Figure 1 is a view, in elevation, of the discharge side of a car, showing one practical embodiment of my new separable rail closure; Fig. 2 is a similar view of one-half of a car and of a somewhat modified form of the closure; Fig. 3 is a view, in side elevation, of a car in which is embodied a further modification of my improved discharge closure; Fig. 4 is a partial elevation of one end of the car shown in Fig. 3, showing a means for locking and releasing the locking-bar; and Fig. 5 is a view similar to Fig. 4, of a modification of such locking and releasing means.

As therein illustrated, A is the underframe of the car, B, B are the steel channel corner stakes of its end walls, C, C are the two sections of the separable horizontal rail, and D, D are the stakes or vertical members of the closure. The rail sections are preferably

105

110

of suitable rolled steel shapes, such as the channels shown. They may be hinged to the corner stakes by any suitable means, but a hinge member 1 which is attached to the 5 outer-end of the rail section and is pivoted to the head of an eye-bolt 2 swiveled in a bearing-block 3 on the outer flange of the corner post provides a convenient flexible connection which permits the sections to 10 drop as they swing outwardly. The bar 4, which is set in keepers 5, 5 on the rail sections, joins the two sections and renders the rail rigid against outward lateral pressure, while locking-pins 6, 6 (Fig. 1), plugged 15 into registering holes in the bar and the flanges of the rail sections, prevent the dropping of their inner ends. The locking-pins or some equivalent means for holding the rail sections in horizontal alignment are 20 necessary where the hinge connections are flexible and where, as shown in Fig. 1, the rail serves merely to brace and is not attached to the stakes D, D, which are supported only at their lower ends, in the releasing stake-pockets 7, 7. If the stakes are 25 bolted to the rail sections, as shown at 6', 6', Fig. 2, nothing of the kind is necessary since the stakes, resting on the bottoms of the pockets, serve to hold up the center of the 30 rail.

In the modification shown in Fig. 3, the rail sections C', C' are longer and overlap for a substantial distance at their inner ends 35 8, 8, one of the two channel sections being wider so that its flanges will straddle the flanges of the other, and give lateral rigidity to the jointure. The four stakes D', D' are 40 arranged in pairs and the stakes of each pair are attached at their upper ends to a rail section and at their lower ends are joined by a horizontal connecting member 9. A locking-bar 10, with lever-arm 11 and an offset 12 opposite the connecting member of each pair of stakes, is swiveled to the side 45 of the underframe in eye-bolts 13 and serves to lock the stakes to the underframe not only against lateral movement but also, in cooperation with a pin 14 set in each connecting member 9, against movement either up or 50 down, thereby giving firmness and rigidity to the closure. The release of the locking-bar simultaneously releases all of the stakes which, as they are thrown out and drop, open up the jointure of the rail sections and so 55 clear the side of the car. To secure the locking-bar in locking position, its lever-arm is caught and held against the web of the corner stake by the hooked end 15 of a rod 16 which is swiveled in the web of the corner 60 stake and the flange of a middle or intermediate stake B' of the wall. As shown in Fig. 4, the rod 16 is held against axial movement by a collar 17 on one side, and a hollow elbow 18 pinned to its end on the other side, 65 of the flange of the stake B'; and it is

rocked, to lock and to release the arm of the locking-bar, by a crank-arm 19 which is pivoted at one end within the outer end of the elbow. The means thus provided for the release of the locking-bar are operable 70 at the end of the car back from its discharge side, where there is no danger of being hit by the outward swing of the rail section and stakes, and its accidental release is effectively prevented by the weight of the pivoted 75 crank-arm 19 and the fact that the hooked rod cannot turn or be turned until the outer end of the crank-arm has been swung clear of the end of a keeper 20 attached to the underframe. In the modification illustrated 80 in Fig. 5 the bent tip 21 of the arm 11 prevents the upward turning of the outwardly pointing hook 15, which must therefore be turned downward to release the locking-bar. To effect this the crank-arm 19, which is here 85 pivoted between the lugs of a member 18 pinned to the end of the rod 16, is swung around and up, to the vertical position shown in dotted lines, and is then drawn away from the wall of the car; and, because 90 of the sheathing plate of the wall, the hook cannot by any change be turned to release the arm of the locking-bar until the crank-arm has been swung around through an arc 95 of nearly ninety degrees. 95

It is to be understood that the invention may be further modified in its various details, within the scope of the appended claims.

What I claim as new, and desire to secure 100 by Letters Patent, is—

1. In a vehicle of the character described, the combination with an underframe and two spaced walls of a discharge closure comprising a separable horizontal rail the two 105 sections of which are respectively hinged at their outer ends to the walls and at their inner ends are releasably joined to withstand outward lateral pressure.

2. In a vehicle of the character described, the combination with an underframe and two spaced walls of a discharge closure comprising a separable horizontal rail the two 110 sections of which are respectively hinged to the walls near the top thereof and at their inner ends are releasably joined to withstand outward lateral pressure and a plurality of stakes which at their lower ends are 115 releasably supported on the underframe and at their upper ends are braced outwardly by 120 the rail.

3. In a vehicle of the character described, the combination with an underframe and two end walls of a discharge side closure comprising a separable top rail the two 125 sections of which are respectively hinged at their outer ends to the walls to swing outwardly thereon and at their inner ends are releasably joined to withstand lateral pressure, a plurality of stakes, and means for 130

locking the lower ends of the stakes to the underframe which are operable to simultaneously release all of the stakes.

4. In a vehicle of the character described, the combination with an underframe and two end walls of a discharge side closure comprising a separable rail of channel sections which are flexibly hinged at their outer ends to the corner stakes of the respective walls, to swing outwardly and downwardly thereon, and which overlap at their inner ends with the flanges of one section straddling the flanges of the other, one or more stakes which at their upper ends are attached to each rail section to swing therewith, and means for locking the lower ends of the stakes to the underframe which are adapted to release all of the stakes simultaneously.
5. In a vehicle of the character described, the combination with an underframe and two end walls of a discharge side closure comprising a separable horizontal top rail of channel sections which at their outer ends are hinged by universal joint connections to the corner stakes of the respective walls, to swing outwardly and downwardly thereon, and at their inner ends overlap with the flanges of one section straddling the flanges of the other, a plurality of stakes which at their upper ends are rigidly attached to the rail sections to swing therewith, a locking-bar which is adapted to lock the lower ends of the stakes to the underframe, in manner to secure the stakes and rail sections against vertical movement, and to release the stakes simultaneously, and means for securing the locking-bar in locking position which are operable at the end of the vehicle back from its discharge side to release the locking bar.

6. In a vehicle of the character described, the combination with an underframe and

two end walls of a separable side closure the two sections of which are respectively hinged to the walls to swing outwardly thereon about vertical axes, and means for locking said closure sections to the underframe which are operable at the end of the car for releasing the locking means and which are effective to prevent any accidental release thereof.

7. In a vehicle of the character described, the combination with an underframe and a wall fixed thereon of a discharge closure which includes a stake attached at its upper end to a member hinged to an end of the wall, to swing outwardly thereon, and means for locking the lower end of the stake to the underframe which are releasable by means operable on the outer side of the wall and from a position back from that end thereof to which the closure member is hinged.

8. In a vehicle of the character described, the combination with an underframe and a wall rigidly supported thereon of a discharge closure which includes a member hinged to an end of the wall to swing outwardly thereon, means for locking the closure in closed position which include a locking-bar swiveled to the edge of the underframe, and means for securing the locking-bar in locking position which include a hooked rod swiveled horizontally to the outside of the wall and extending inwardly to a point intermediate its side, a crank pivotally attached to the inner end of the hooked rod to normally hang vertically downward when the hook on the rod is in operative position, and means for preventing the turning of the hooked rod until the crank has been swung around on its pivot through a substantial arc.
